UNITED STATES PATENT OFFICE.

JOHN H. JOHNSON, OF SANTA BARBARA, CALIFORNIA.

BAKER'S MATERIAL-CABINET.

1,329,607.

Specification of Letters Patent.

Patented Feb. 3, 1920.

Application filed February 3, 1919. Serial No. 276,183.

To all whom it may concern:

Be it known that I, JOHN H. JOHNSON, a citizen of the United States, residing at Santa Barbara, in the county of Santa Barbara and State of California, have invented 5 a new and useful Baker's Material-Cabinet, of which the following is a specification.

My invention relates to material cabinets, being more particularly a cabinet for containing materials commonly used in bake 10 shops. In most shops of this kind the various materials used are scattered about the shop in boxes, barrels and cans, on shelves and similar places, and a great amount of 15 time is lost in getting the materials together required in the preparation of the baking. Then again, as ordinarily no special provision is made for the handling of these materials it frequently happens that the materials 20 are spilled about the floor which not only makes the place unpleasant to work in but also results in considerable loss of material.

The principal object of my invention is to 25 make a material cabinet of simple form and construction arranged to hold all the materials required for use in preparing pies, cakes, bread and similar articles, and which may be used by workers on both sides of the 30 cabinet, it being also one of the objects to have both sides of the cabinet substantially alike for that purpose.

Other objects and advantages will be made 35 evident hereinafter.

Referring to the drawings which are for 40 illustrative purposes only,

Figure 1 is a perspective view illustrating a cabinet embodying a form of my invention.

Fig. 2 is a side elevation partly in section 45 of the cabinet shown in Fig. 1.

Fig. 3 is a plan view of the cabinet.

Fig. 4 is an end elevation partly in section 50 of the cabinet.

Fig. 5 is a face view partly in section of 55 a wall cabinet.

Fig. 6 is a plan view of the cabinet shown 60 in Fig. 5, and

Fig. 7 is an end elevation of the cabinet 65 shown in Figs. 5 and 6.

The cabinet is preferably built of wood 70 and consists in general of a lower section 11 and an upper section 12, the cabinet being provided with rollers 13 by means of 75 which the cabinet may be easily moved if desired. The lower section 11 is provided

with a top 14 having a flat central portion 15 upon which the upper section 12 is secured in any suitable manner. The top 14 is provided at each side of the central portion 60 15 with a series of covers 16 hinged to the top as shown at 17, each cover 16 forming the top of one of a series of bins 18 on each side of the cabinet, which bins are used for flour, sugar, salt, and similar materials. 65

Under the bins on each side of the cabinet is a series of drawers 19 to be used for various materials such as walnuts, raisins, peanuts, lemons, citron, etc. On one side of the cabinet in the central portion thereof, between the bins and the drawers above referred to, are arranged two boards 20 and 21 which slide into the cabinet in suitable guides 22, these boards being designed to be removable from the cabinet and used for 75 boards upon which to roll cookies, doughnuts and pie dough, after which they are returned to the cabinet.

The upper section 12 is provided with a series of drawers 24 which are arranged to 80 slide entirely through the cabinet so that access may be had to such drawers from either side of the cabinet, these drawers having drawer pulls 23 of the form having a holder upon which a card may be placed 85 designating the contents of the drawer, it being a common form of drawer pull and therefore not shown in detail. These drawers are for the purpose of containing spices, seeds, baking powders, soda and such material. 90

The central part of the upper section 12 is built up to form an elevated section 25 having two drawers 26 slidably mounted 95 therein on each side of the cabinet. 30 designates a slide or board slidable through the upper section between the drawers 24 and the drawers 26. The slide or board 30 is operated from either side of the cabinet and is for the purpose of holding a receptacle (not shown) while being filled from cans or containers 31 placed upon a rotatable table 32 mounted upon a vertical shaft 33 which rotatably extends into the elevated section 25 as clearly shown in Figs. 2 and 4. 100 It is understood that the table 32 may be rotated to bring the can holding the desired material into proper position above the receptacle placed on the board 30 so that the same may be filled, the board 30 serving 105 for this purpose on both sides of the cabinet. 34 designates holders for rolling pins, 110

such holders being mounted on the upper section in any suitable manner, and 35 designates a rib or ledge formed on the top of the upper section so that utensils placed thereon are retained from falling from the cabinet. The ribs 35 do not extend to the ends of the upper section, leaving a portion 36 on the top of the upper section at each end of the cabinet clear so that a can may be placed thereon as shown in Fig. 1, the faucet of the can extending beyond the cabinet and in a position to deliver the contents of the can into a measure 37 supported on a slide 38 mounted in the end of the cabinet, there being such a slide in each end of the cabinet for this purpose. There is also arranged a lower slide 40 in each end of the cabinet for the purpose of holding the tub of material as shown at one end of the cabinet in Fig. 1. By the above description and drawings it will be readily seen that all of the material required by the baker is at hand where it may be economically used and that two crews may work from the same cabinet, one crew working on each side of the cabinet.

On each end of the cabinet are pegs 41 which are suitably arranged to receive sieves and pans and other utensils used in the shop. In the form of cabinet shown in Figs. 5, 6 and 7 the lower section 50 is provided with a series of bins 51 each provided with a hinged top 52, there being a series of drawers 53 under the bins and a pastry board 54, all of which are similarly arranged to the like parts described in connection with the preceding figures. This form of cabinet also has an upper section 55 having therein a series of drawers 56. 57 designates a board below an elevated section 58 upon which is mounted a rotatable table 59, the elevated section 58 having drawers 60 therein.

61 designates the back of the case upon

which is mounted shelves 62, brackets 63 for rolling pins and similar articles, and 64 designates a series of pegs upon which utensils may be hung. 65 designates a board 66 slideable into the end of the cabinet and 66 designates a series of drawers in the end of the cabinet.

What I claim is:—

1. In a cabinet having like sides of drawers and bins having a rotatable table mounted on said cabinet, and a board slideable through the cabinet below the rotatable table arranged to project outwardly beyond the table when in extended position on either side of the cabinet.

2. In a material cabinet having drawers and bins for materials, a rotatable table mounted on top of the cabinet, and a board slideable through the cabinet below the rotatable table arranged to project outwardly beyond the table when in extended position on either side of the cabinet.

3. In a material cabinet having like sides of drawers and bins, a lower section, an upper section mounted on the lower section, a rotatable table mounted on the top of the upper section and a board slideably mounted in the upper section arranged to project outwardly beyond the table when in extended position on either side of the cabinet.

4. In a material cabinet having like sides of drawers and bins, a lower section, a series of bins in the lower section, hinged tops for said bins forming a part of the top of said lower section, and an upper section on said lower section between the tops of said bins forming a stop for the tops of the bins when in open position.

In testimony whereof, I have hereunto set my hand at Santa Barbara, California, this 31st day of January, 1919.

JOHN H. JOHNSON.
